UNITED STATES PATENT OFFICE.

RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR ON TRANSFERRER WITH AUXILIARY DETECTOR.

Application filed July 21, 1926. Serial No. 124,047.

This invention relates to improvements in weft detectors for looms and more particularly to the type employed in regularly moving transmitters for weft replenishing looms.

In Patent No. 1,372,816 to Ryon there is shown a loom having a regularly reciprocated transmittor arm which is moved down to present a detector carried thereby to the upper surface of the bobbin on each detecting pick of the loom and in co-pending application Ser. No. 78,181 there is shown a modification of this type of feeler wherein a spring pressed plunger is locked by a pivoted latch or hook member which is tripped to release the plunger at the time of substantial exhaustion of weft. It has been found that detectors of this type are prone to move toward and accidentally release the latch and it is the principal object of the present invention to supply a yarn engaging device for the latch which will hold said latch from accidental indicating movement so long as sufficient weft is present.

It is a further object of my invention to provide the plunger holding latch with an auxiliary detector the purpose of which is to prevent releasing of the plunger should the latch be accidentally engaged by the primary detector when sufficient yarn is present.

The invention is set forth in connection with the type of detector shown in my co-pending application Ser. No. 120,491 wherein the energy stored in a moving detector is brought into play at the time the transmittor comes to rest to exert a force on the detector tending to give the latter an indicating movement, but it is to be understood that the auxiliary detector shown herein may be used in conjunction with the types of motions set forth in the co-pending applications heretofore mentioned and that I am not limited to the particular type of primary detector shown herein, it being sufficient for the present invention to have the detector movable in the direction of the length of the bobbin at the time of indication of weft exhaustion.

With these and other objects in view which will appear as the description proceeds, my invention resides in the combination and arrangement of parts hereinafter described and set forth in the claims.

In the accompanying drawings wherein I

have shown a convenient embodiment of my invention,

55

Fig. 1 is a vertical section through that portion of the transmittor arm which extends over the shuttle when the latter is boxed on the magazine side of the loom and having my invention applied thereto, showing the detector in contact with a bobbin having sufficient weft thereon,

Fig. 2 is a view similar to Fig. 1 but with the detector in contact with a substantially exhausted bobbin and showing the parts in 65 the position they assume when indicating weft exhaustion, and

Fig. 3 is a detail vertical section on line 3-3 of Fig. 2.

Referring to the drawings it will be seen 70 that I have provided a transmittor arm 10 having an extended portion 11 lying above and parallel to the axis of the shuttle and bobbin. A plunger 12 is slidably mounted in a portion of the transmittor arm and has 75 a shoulder 13 which receives the inner thrust of a compression spring 14 the outer end of which bears against a clip 15 held to the transmittor arm by screw 16. The plunger 12 is provided with a head 17 which engages 80 the clip to limit inward movement of the plunger under the action of spring 13.

A latch 18 is pivoted as at 19 to the transmittor arm and moves in a vertical slot 20 extending through the arm, said latch having a hook 21 which normally engages the head 17 to hold the parts in the position shown in Fig. 1. A spring 22 tends normally to move the latch in a right hand direction around its pivot so that a depending 90 finger 23 of the latch will normally occupy the position shown in Fig. 1.

The detecting element indicated at 24 is pivoted as at 25 to a lever 26 moving in the slot 20 about a stud 27 extending across said slot and secured to the transmittor arm. A boss 28 on the lever 26 serves to stop a set screw 29 passing through an extension 30 of the detector to limit right hand motion of the detector about its pivot. A tension 100 spring 31 is connected to the extension 30 and has the straightened part thereof passed through an ear 32 and held therein in adjusted position by a set screw 33. The matter thus far described is substantially the 105 same as that set forth in several co-pending

22 applications, such for instance, as Ser. No. 78,181.

As previously stated the type of detector chosen to show one embodiment of my present invention depends for its operative movement upon the inertia of the supporting lever 26 and in order to hold the latter in normal raised position I provide a tension spring 40 having an end straightened and passing through a portion of the trans- 10 ferrer arm and secured thereto by a screw 41 and having the other end secured to a horn 42 preferably cast integral with the lever 26. A tail 43 extends to the right of the 15 stud 27 and engages a portion of the trans- ferrer arm to limit upward movement of the 20 lever 26 under action of screw 40. The matter heretofore described may be substantially the same as that set forth in the patent and applications previously indentified and forms no part of my present invention.

In carrying out my present improvements I mount an auxiliary detector plunger 50 in the finger 23 and provide said plunger 25 with a guide pin 51 which moves in a vertical slot 52 formed in the finger 23. The upper part of the latch is provided with a cap plate 53 secured in place by a screw 54 and positioned to limit downward move- 30 ment of a cotter pin 55 extending through the upper reduced end 56 of the auxiliary detector 50. A compression spring 57 surrounds the reduced end 56 and lies between the cap 53 and the lower head portion of 35 the auxiliary detector. The latter may be formed wedge-shaped, the pin 51 serving to align the penetrating edge of the auxiliary detector with the coils of yarn. Under normal conditions the parts are in the 40 position indicated in Fig. 1 with the plunger 12 retained in locked position by engagement of the head 17 and hook 21, a continuance of this position being insured by the action of spring 22. The auxiliary plunger de- 45 tector 50 will be in its lowest position relatively to the finger 23 and the detector 24 will be spaced from the finger as indicated in Fig. 1. As the trans- ferrer arm is brought to a sudden stop as it approaches the bobbin 50 B the detector 24 and supporting lever 26 will continue in their downward movement by reason of the inertia of the lever 26 and the detector will tend to move lengthwise along the bobbin to give an indication of 55 weft exhaustion. The roughened surface of the detector will ordinarily prevent this movement but should the detector slip on a sufficient supply of weft so as to engage the finger 23, angular movement of the latch 60 18 will be prevented because of the fact that the auxiliary detector 50 will have entered the yarn on the bobbin. Locking en- gagement between the head 17 and the hook 21 will therefore be maintained under these 65 conditions.

As soon as insufficient weft for continued weaving appears under the trans- ferrer arm the detector 24 will slide along the bobbin to the position indicated in Fig. 2 and will engage the finger 23 and move the latter 70 in a counterclockwise direction about the pivot 19 against the action of spring 22. Inasmuch as there is insufficient yarn to engage the auxiliary plunger 50 and restrain sliding movement thereof said plunger will 75 not resist angular movement of the latch and the latter will therefore be moved to the position indicated in Fig. 2, hook 21 releasing head 17 and spring 14 moving plunger 12 to the position shown in Fig. 2. 80 This position, as set forth in Patent No. 1,372,316, corresponds to an indication to the weft replenishing mechanism. Upon a subsequent upward movement of the trans- ferrer arm the plunger 12 will be returned 85 to the position shown in Fig. 1 by mechanism not shown but set forth in the afore- said patent, and spring 22 will serve to re- turn the latch to normal holding position.

From the foregoing it will be seen that I 90 have provided a trans- ferrer with a primary weft detector and have furthermore pro- vided an auxiliary detector associated with the latch which holds the plunger in in- operative position, the auxiliary detector 95 preventing premature indication of weft ex- haustion but permitting proper indicating movement of the detector when the weft has been depleted to a predetermined degree.

Having thus described my invention it 100 will be apparent that changes and modifi- cations may be made therein by those skilled in the art without departing from the spirit and scope of the invention, and I do not 105 wish to be limited to the details herein disclosed but what I claim is:

1. In a weft detector for a loom having a regularly moving trans- ferrer arm and a surface to be detected, an indicating plunger mounted thereon, a latch to hold said plunger in inoperative position, a primary weft detector having a movement toward the latch when indicating weft exhaustion, and an auxiliary detector operatively related to the latch and engaging the surface to be de- 110 tected to prevent improper movement of the latch should the primary detector have a premature latch engaging movement.

2. In a weft detector for a loom having a regularly moving trans- ferrer arm and a surface to be detected, a member receiving a regular movement toward the surface to be detected, a primary detector mounted on the member and presented to the surface to be detected on detecting beats of the loom, an indicating element movable on the trans- ferrer arm, a locking device to hold the element normally in inoperative position, and an auxiliary weft detector operatively re- 115 lated to the locking device and engaging 120 125 130 135

the surface to be detected to prevent unlocking movement of the locking device should the latter be engaged by the primary detector when sufficient weft is present.

- 5 3. In a weft detector for a loom having a regularly moving transerrer arm and a surface to be detected, a weft detector supported by and movable with respect to the transerrer arm and having an indicating 10 movement along a substantially exhausted bobbin, a spring stressed plunger slidably mounted on the transerrer arm, a piv-

oted latch normally holding the plunger in inoperative position, and an auxiliary detector mounted on and movable with respect to the latch and engaging the surface to be detected to prevent unlocking movement of the latch relatively to the plunger should the primary detector engage the latch when sufficient yarn is present. 15 20

In testimony whereof I have hereunto affixed my signature.

RICHARD G. TURNER.
